CANDLEHOLDER

Bertram Suall, 330 3rd Ave., New York, N.Y.

Filed June 25, 1965, Ser. No. 85,905

Term of patent 14 years

(Cl. D48—2)

FIG. 1.

FIG. 3.

FIG. 2.

FIG. 4.

I claim:

The ornamental design for a candleholder, as shown and described.
